UNITED STATES PATENT OFFICE.

JOHN C. WOODCOCK, OF CHILlicothe, OHIO.

GRINDING-MILL.

No. 839,248.

Specification of Letters Patent.

Patented Dec. 25, 1906.

Application filed June 11, 1904. Renewed September 19, 1906. Serial No. 335,312.

To all whom it may concern:

Be it known that I, JOHN C. WOODCOCK, a citizen of the United States, residing at Chillicothe, in the county of Ross and State of Ohio, have invented certain new and useful Improvements in Grinding-Mills; and I do hereby declare the following to be a full, clear, and exact description of the invention, such as will enable others skilled in the art to 5 o which it appertains to make and use the same.

The object of the present invention is to make an improvement upon the type of mill illustrated in my patents of the United States, 15 No. 546,869, dated September 24, 1895, and No. 610,220, dated September 6, 1898. In such mills it is desirable that they be adapted to grind both coarse and fine—coarse for the cattle and fine for the family of the farmer. 20 To accomplish this, it has been my practice to attach to the revolving cone either a fine-grinding or a coarse-grinding ring, the change being made by substitution. This substitution, however, involved extensive segregation 25 of the parts of the mill, and not only consumed much valuable time, but also involved considerable mechanical skill. In my present mill herein set forth the change from coarse grinding to fine grinding and the reverse involves little more than the raising and lowering of a lever.

In the accompanying drawings, in which I have illustrated one embodiment only of the invention, Figure 1 is a central vertical sectional view showing the parts set for fine grinding. Fig. 2 is a view of the lower portion of the mill, showing the parts set for coarse grinding. Fig. 3 is a horizontal section on the plane $x-x$, Fig. 1, looking down. 30 Fig. 4 is a similar view on the same plane looking up. Fig. 5 is a fragmentary detail, partially in section, on the plane $y-y$, Fig. 1, showing the spider-ring that supports the hopper.

45 1 designates the hopper, 2 the spider-ring that has a perforated hub 3, said ring supporting at its edge the hopper 1. The horse-power lever that revolves the hopper is attached to this spider-ring. 4 designates the 50 outer cone or shell, having at its upper end a spider that supports the spider-ring and hopper. Within the shell is a coarse outer grinding-ring 4^a and a fine outer grinding-ring 4^b, the former supported above the latter and both held stationary by means of lugs there-

on entering grooves 4^c in the inner wall of the outer cone or shell.

6 designates the inner cone that has projecting upward from its apex a stem 7, provided with splines 7^a, engaging grooves in the hub of the spider-ring, so that the inner cone will be revolved with the spider-ring. The inner cone carries on its lower edge a coarse-grinding ring 6^a, that coöperates with the coarse-grinding ring 4^a. The inner fine-grinding ring that coöperates with the outer fine-grinding ring is designated 6^b. The inner coarse-grinding ring is provided with hooks 4^d, that are adapted to catch under lugs 6^d on the inner fine-grinding ring 6^b. The inner fine-grinding ring is provided with a diametric bridge-bar 6^e, in the center of which is a bearing to receive the upper end of a dead-spindle 7^b. This spindle is supported on a lever 8, pivoted in a hanger at one side of the base-frame 9 of the mill and having its other or free end resting on an adjustable support 10 at the other side.

Supported on the base 9 below the opening between the grinding-rings is shown a circular trough 11, having a discharge-opening 11^a, and within the trough is a revoluble bladed wheel 12, adapted when revolved to carry the ground material to the discharge-opening. The means for carrying the bladed wheel around can consist of a finger 6^f, secured to and reaching down from the cone 6 through the inner fine-grinding ring into position to contact with one of the blades.

The operation is as follows: With the construction shown the hopper and inner cone and grinding-rings are turned with a so-called "haw" draft. When it is desired to grind fine, the lower inner ring is raised to the position indicated in Fig. 1, and when so raised the hooks 4^d of the upper inner ring catch under the lugs 6^d of the lower ring. When it is desired to grind coarse, the lower fine-grinding ring is depressed, as seen in Fig. 2. This can be accomplished by turning the hopper slightly backward, so as to disengage the hooks 4^d from the lugs 6^d and depressing the lever 8. When the mill is grinding coarse, the inner fine-grinding ring is at rest. It will be observed, therefore, that to change the mill from fine to coarse grinding it is only necessary to adjust the lever 8. The coarse-grinding ring 6^a can be adjusted to vary the degree of coarseness of the product by raising and lowering the inner cone 6, which car-

ries the inner grinding-ring, a handled nut 13, working on a screw 15 in the stem 7, being provided for this purpose. The fine-grinding ring 6^b when hung on the hooks 4^d can also be adjusted to vary the degree of fineness of the product by the same means.

Changes in the form of the parts shown can be made without departing from the gist of the invention.

10. What I claim, and desire to secure by Letters Patent, is—

15. 1. In a grinding-mill of the kind described, the combination of a casing, an outer coarse-grinding ring and an outer fine-grinding ring below the coarse-grinding ring within said casing, an inner coarse-grinding ring to coöperate with the aforesaid outer coarse-grinding ring, means for rotating said inner coarse-grinding ring, means for adjusting said coarse-grinding 20 ring to vary the coarseness of its grinding, means for stationarily supporting and for raising and lowering said inner fine-grinding ring independently of the inner coarse-grinding ring and means for locking said inner fine-grinding ring to the coarse-grinding ring only when said inner fine-grinding ring is raised to coöperate with the inner fine-grinding ring.

25. 2. In a grinding-mill of the kind described, the combination of a casing, an outer coarse-grinding ring and an outer fine-grinding ring below the coarse-grinding ring within said casing, an inner coarse-grinding ring to coöperate with the aforesaid outer coarse-grinding ring, means for rotating said inner coarse-

30. grinding ring, means for stationarily supporting and for raising and lowering said inner fine-grinding ring independently of the inner coarse-grinding ring and means for locking said inner fine-grinding ring to the coarse-grinding ring only when said inner fine-grinding ring is raised to coöperate with the inner fine-grinding ring.

35. 3. In a grinding-mill of the kind described, the combination of a casing, an outer coarse-grinding ring and an outer fine-grinding ring below the coarse-grinding ring within said casing, an inner coarse-grinding ring to coöperate with the aforesaid outer coarse-grinding ring, means for rotating said inner coarse-grinding ring, means for stationarily supporting and for raising and lowering said inner fine-grinding ring independently of the inner coarse-grinding ring, means for locking said inner fine-grinding ring to the coarse-grinding ring only when said inner fine-grinding 40 ring is raised to coöperate with the inner fine-grinding ring, the circular trough 11 below the discharge-opening of the rings, the bladed wheel 12, and the finger 6^f reaching through the fine-grinding ring and engaging the bladed 45 wheel 12 to revolve the same.

45. In testimony whereof I affix my signature in presence of two witnesses.

JOHN C. WOODCOCK.
